GENERATING BAFFLE

Daniel E. Wegner, Mina, S. Dak.

Application August 3, 1939, Serial No. 288,217

6 Claims. (Cl. 158—91.)

This invention relates to an improved heat generating baffle for oil burning heaters.

More particularly, it is an aim of this invention to provide a heat generating baffle for use in oil burner pots of the type provided with a plurality of rings of perforations in its side wall and a fire ring mounted within the burner and disposed between the top and bottom thereof, for generating heat in the bottom of the pot to more efficiently vaporize the oil contained therein.

Still a further aim of the invention is to provide a heat generating baffle of the type described adapted to efficiently function to confine the heat of a low fire by increasing the heat in the bottom 10 of the pot through reduction of the effect of the chimney draft.

Still another aim of the invention is to provide a heat generating baffle which will be disposed below a high fire, in a burner of the class described, but which will be sufficiently heated thereby to maintain sufficient heat in the bottom 15 of the pot to completely vaporize the oil contained therein.

Other objects and advantages of the invention 20 will hereinafter become more fully apparent from the following description of the drawings, which illustrate a preferred embodiment thereof, and wherein:

Figure 1 is a vertical central sectional view 25 of a conventional form of oil burner showing the invention, in elevation, mounted therein,

Figure 2 is an enlarged top plan view of the invention,

Figures 3 and 4 are transverse vertical sectional views taken substantially along the lines 3—3 and 4—4, respectively, of Figure 2,

Figure 5 is a horizontal sectional view taken substantially along the line 5—5 of Figure 3,

Figure 6 is a fragmentary side elevational view 40 of a portion of the device, and

Figure 7 is a fragmentary central sectional view 45 of a slightly modified form of the invention.

Referring more particularly to the drawings, wherein like reference characters designate like or corresponding parts throughout the different views, 10 designates generally a conventional type of oil burner having a solid bottom portion forming a pot 11 adapted to contain oil supplied thereto by means of the conduit 12. Burner 10 also includes a cylindrical side wall 13 which rises from the top of the pot 11 and which is provided with a plurality of rings of spaced perforations 14. Burner 10 also includes a lower fire ring 15 which extends inwardly from the cylindrical wall 13 intermediate of its top and bottom

and intermediate of the rows of perforations 14. The ring 15 is provided with a central opening 16. The burner 10 is enclosed by a cylindrical walled casing 17 which is concentrically disposed relatively thereto and which is provided with an opening 18 in its bottom portion arranged coaxially with the burner 10 and spaced beneath the bottom of the pot 11. Wall 13 is provided with an annular flange 19 at its top, provided with a downturned annular portion 20 which 10 is secured to casing 17 by the fastenings 21 to close the passage between burner 10 and casing 17 so that air entering opening 18 in order to reach the top portion of the casing 17, above the burner 10, must pass through the perforations 14. The parts heretofore described are all 15 of conventional construction and have been illustrated and described merely to explain the construction and function of the invention which will hereinafter be described.

The invention, designated generally 22, comprises a heat generating baffle formed entirely of metal which is preferably relatively thin to more readily transmit heat. The generating baffle 22 includes the disk shaped members or plates 23, 25 which are preferably circular and provided with the radial outwardly diverging openings 24 forming the hub portions 25, rims 26 and connecting spokes 27. The disks 23 are connected by means of the fastenings 28 which extend through the 30 rims 26 and are held in spaced apart relationship by the sleeves 29 carried by the fastenings 28. The disks are arranged in their connected position so that their hub portions 25, openings 24, rims 26 and spokes 27 are in alinement, as best 35 seen in Figure 2. The generating baffle 22 also includes a member, designated generally 30, which is disposed between the disks 23 and which includes a hub portion 31 and a plurality of blades 32 which extend radially therefrom. Blades 32 40 are formed integral with the hub 31 and are twisted, at 33, relatively thereto so that the plane of the blades 32 is substantially at right angles to the plane of the hub 31. As best seen in Figures 3 and 4, the blades 32 diverge toward their free ends and are connected, adjacent their free ends, by a ring 34 which extends through each of the blades 32. As best seen in Figure 6, the inner sides of the rims 26 are provided with notches 35 in which the opposite edges of the 45 outer ends of the blades 32 are seated to rigidly mount the member 30 between the disks 23. The rim 26 of one of the disks 23 is provided with the inwardly projecting members 36 having the 50 outwardly projecting free ends 37 forming lugs 55

for engaging the inner portion of the fire ring 15 for mounting the generating baffle 22 in the opening 16, thereof, as illustrated in Figure 1.

In Figure 7 a slightly modified form of the baffle 22 is illustrated, wherein the hub portion 25 of the upper disk 23 is provided with a central opening 38.

In the operation of the burner 10, the flame initially is in the bottom of the pot 11 and as the heat of the burner increases the flame moves upwardly step by step to the topmost row of perforations 14. This movement of the flame from a low fire to a high fire will occur before the pot 11 is sufficiently heated due to the chimney draft 15 caused by the air entering the opening 18 and into the burner 10 through the perforations 14 so that when the flame reaches the uppermost row of apertures 14, or the high fire stage, the pot is not sufficiently heated to properly vaporize 20 the oil to obtain the maximum heat from the oil being used thereby rapidly causing the formation of carbon. The generating baffle 22 in the initial stage of the flame, or in the low fire stage, functions to hold the heat in the pot 11 to thereby 25 heat the pot to a greater degree and to decrease the effect of the chimney draft to produce a clean blue burning low or medium fire of substantially the same efficient performance of a high flame fire. After the flame has risen above the generating baffle 22 this baffle will still continue to be heated by the flame and the heat therefrom will radiate from the blades 32 to maintain a high temperature in the pot 11 so that the oil contained therein will continue to be vaporized 30 not only to produce a better high fire flame but to minimize the accumulation of carbon and the resulting waste.

Various modifications and changes are contemplated and may be resorted to, as the drawings and description are only intended to illustrate a preferred embodiment of the invention, the scope of which is hereinafter defined by the appended claims.

I claim as my invention:

45 1. A device of the class described comprising

a pair of disks having radially disposed outwardly diverging openings, means for mounting said disks in spaced apart relationship relatively to each other with said openings in alignment, and a plurality of blades disposed between said disks, said blades bisecting the aligned openings. 5

2. A device as in claim 1, comprising a plurality of outwardly projecting supporting lugs secured to said device.

3. A heat generating baffle for liquid fuel burners, comprising a pair of corresponding circular members, each of said circular members including a hub portion and rim connected by a plurality of spokes forming spaced outwardly diverging openings therebetween, means for securing said members in spaced apart relationship with said openings in alignment, a plurality of radially disposed blades mounted between said circular members and disposed between said diverging openings, and supporting lugs secured to one of said circular members and having free ends projecting outwardly from between said circular members. 10 15 20

4. A device as in claim 3, the hub portion of the upper circular member being provided with a central opening. 25

5. In a heat generating baffle, a pair of corresponding plates provided with a plurality of radially disposed outwardly diverging openings, means for connecting said plates in spaced apart relationship with said openings substantially in alignment, a hub, and a plurality of blades radiating therefrom, said blades being formed integral with said hub and having their planes disposed substantially at right angles to the plane 30 35 of said hub, said hub and blades being fixedly secured between said plates with each of said blades disposed between corresponding openings of said plates.

6. A device as in claim 5, said blades diverging 40 outwardly from said hub, and a ring extending through each of the blades adjacent its free end.

DANIEL E. WEGNER. 45
